UNITED STATES PATENT OFFICE.

NORWOOD A. RICHARDS, OF MOBILE, ALABAMA.

WINCH FOR MOTOR-VEHICLES.

1,098,762.

Specification of Letters Patent. Patented June 2, 1914.

Application filed February 11, 1913. Serial No. 747,661.

To all whom it may concern:

Be it known that I, NORWOOD A. RICHARDS, a citizen of the United States, and a resident of Mobile, county of Mobile, State 5 of Alabama, have invented certain new and useful Improvements in Winches for Motor-Vehicles, of which the following is a full and clear specification, reference being had to the accompanying drawings, in which—
10 Figure 1 is a side elevation of my device and a sufficient number of the parts of a motor vehicle to illustrate its use; Fig. 2 a plan view of the same; Fig. 3 a vertical transverse section on the line 3—3 of Fig. 1; 15 and Fig. 4 a plan view of a slightly modified arrangement of the gearing.

The object of this invention is to provide a motor vehicle with a power winch by which the power developed by the engine of 20 the vehicle or the starting motor may be used for the purpose of hauling the car out of mud holes or ruts, up steep grades and out of ditches, where ordinary tractive power of the wheels would not be sufficient 25 for that purpose.

In the drawing *a* designates the usual engine shaft carrying the fly wheel *b*, *c* the usual transmission shaft adapted to be coupled to the engine shaft through the medium 30 of the clutch member *d* in the usual manner, *e* the usual transmission gear box and *f* the usual propeller shaft.

Affixed to the transmission shaft *c* is a gear *g* and meshing with the same is another 35 gear *h*, this latter gear being slidably mounted on a shaft *i*, the connection being such that while the gear may slide on the shaft it shall rotate with it. This gear *h* may be shifted into and out of mesh with the gear *g* 40 by the usual fork *j* or by other suitable means. The shaft *i* lies parallel with the propeller shaft and is journaled in a suitable bracket *k* bolted to the inner face of the adjacent frame bar *l* of the vehicle. Af- 45 fixed to the shaft *i* is a worm *m* which meshes with a worm gear *n* affixed to the shaft of a drum *o*, the drum shaft being journaled in suitable hangers *p* bolted to the under sides of the frame bars of the vehicle, 50 the drum shaft extending entirely across the vehicle and lying at right angles to the transmission shaft.

A wire or other rope *p'* is wound upon the drum and its free end is adapted to be

carried forward and attached to a suitable 55 anchor, such as a stake driven in the ground or a convenient tree or post. To guide this wire or rope and hold it away from the fly wheel I provide a pulley *q* which is suspended at a proper point by means of a pair 60 of bracket arms *r* bolted rigidly to the frame bars of the vehicle, the pulley being free to slide on a rod *q'* so as to wind on the drum properly. It is obvious that this rope *p'* may be carried rearward and attached to 65 an anchor at the rear of the machine if the machine is to be pulled backwardly; in this case a duplicate of the guide pulley *q* may be provided if the construction of the vehicle is such as to require another pulley. 70

In Fig. 4 I show means whereby the power for driving the drum is taken off from one of the gears in the transmission box *w*. To accomplish this I employ a short counter-shaft *s* and mount the sliding gear *h* on one 75 end of it in such position as to be readily shifted into and out of mesh with one of the driving gears of the transmission. The screw shaft *i* is geared to the shaft *s* by means of a pair of gears *t* and *u*. 80

It will be observed that when the engine is started either under its own power or under the power of a starting motor and the clutch of the transmission shaft is closed, the power may be taken off from the transmission shaft to the drum and by means of the worm gear it will be observed that the speed is greatly reduced and that the power is greatly increased. With this type of gearing it will also be observed that a 85 ratchet and pawl mechanism is unnecessary to prevent backward rotation of the drum when the engine is stopped or the clutch is out, the pitch of the worm being such as to prevent the pull on the drum from causing 90 the worm gear to rotate the worm.

It will be observed that in my invention the power for operating the drum is taken off from the transmission shaft, that is, at a point between the engine shaft and the propeller shaft. By reason of this arrangement the chauffeur can control the operation of the drum from his seat since the drum may be started or stopped through the medium of the usual clutch *d*, the gears *g* and 100 *h* first having been brought into mesh in any suitable manner. This arrangement 105 also permits the winch to be operated either

with or without aid of the tractive power of the vehicle, since the drum may be rotated whether or not the transmission gearing be in action. It will be observed also 5 that with my combination of straight gears and worm gears, I may derive the power to drive the drum from any part of the vehicle driving mechanism (for instance, the fly-wheel), although I have illustrated but two 10 ways of driving the drum. It will be observed also that an advantage of my apparatus lies in its accessibility, the gearing being just under the front floor board and being therefore easily reached for oiling, 15 tightening, examination, etc. It will be observed also that it is susceptible of being attached to the frame of the vehicle in a very strong and durable manner. Further, the 20 gearing is adapted to be so located as to be protected by the usual pan, this pan protecting it against mud, dirt, etc. Again, it will be seen that the drum is not in mesh with its source of power except when needed and that consequently there is no wear or 25 tear and rattling of parts may be readily avoided. Furthermore my mechanism will work equally well from the rear as from the front of the vehicle and the driver has absolute control over the vehicle from his seat 30 whether going backward or forward. A further advantage is that the gearing and drum and supporting parts may be standardized, thereby enabling the parts to be manufactured cheaply and readily replaced. 35 It will be seen also that my apparatus is capable of being used with the engine starter, so that the vehicle may be hauled out of a hole even when the engine is stalled.

Having thus described my invention, what

I claim as new and desire to secure by Letters Patent, is—

1. The combination with a motor-vehicle embodying a driving mechanism comprising an engine shaft and a transmission shaft, of a power-winches comprising a winding drum, a self-locking speed-reduction gearing for rotating said drum, and a disconnectible driving-connection between said speed-reduction gearing and one of said shafts, whereby said speed-reduction gearing may be disconnected from the driving mechanism and will hold the drum against rotation while so disconnected. 45

2. The combination with a motor-vehicle embodying a driving mechanism comprising an engine-shaft, a transmission shaft, a disconnectible driving-connection between said shafts, a propelling shaft and a disconnectible driving-connection between the transmission and propelling shafts, of a power-winches comprising a winding-drum journaled in the frame of the vehicle, a self-locking speed-reduction gearing adapted to rotate said winding-drum and a disconnectible driving-connection between the transmission shaft and said speed-reduction gearing, whereby the propelling shaft and power-winches may be driven simultaneously or independently, and whereby the winding-drum will be locked against rotation when disconnected from the driving mechanism. 60

In testimony whereof I hereunto affix my signature in the presence of two witnesses.

NORWOOD A. RICHARDS.
